INSERT HOLDING DEVICE

William A. Hatch, Ashtabula, Ohio, assignor to
Gross Photo Supply Company, Toledo, Ohio, a
corporation of Ohio

Application April 20, 1934, Serial No. 721,559

7 Claims.

(Cl. 40—152)

This invention relates to insert holding devices and is particularly applicable to mounts for detachably displaying such inserts as photographs, menus, advertising cards or the like.

- 5 The primary object of the invention is the provision of means to hold an insert so that it will be advantageously displayed and in such a manner that it will be readily removable from the mount.
- 10 Another object of the invention is to provide a device of the above type which is previously assembled and which is capable of ready use without requiring skillful manipulation.

15 Another object of the invention is to provide an insert holding device which is inexpensive to manufacture, and which is efficient and durable in use.

20 Other objects and advantages of the invention will become apparent as the description proceeds, reference being had to the accompanying drawing in which:

Fig. 1 is an elevation of an assembled insert holding device with the parts in the final retaining position; Fig. 2 is a similar view with parts 25 broken away and with the parts in retracted, or receiving position; Fig. 3 is a composite view of the individual parts showing the imposed relation of the various elements, and Fig. 4 is a section on line 4—4 of Fig. 1 with an insert in place.

30 Referring to the drawing, 1 designates a mount on which the device embodying the invention is assembled, and which mount may be of any suitable type, such as the common easel or book forms well known in the art. A spacing member 2 is 35 fixed to the mount and, in the embodiment shown, comprises a rectangular sheet of material in which the central portion is removed to provide an opening to receive the insert. This opening is approximately the size of the insert with which 40 the device is to be used and serves to retain the insert in centered position in the final assembly. Obviously any spacing member may be used and the continuous form shown may be replaced by individual strips on the four sides or any other 45 suitable device which the skill of the maker may dictate.

Overlying the spacing member 2 and spaced by it from the mount 1 is an underlay comprising in the present instance, stationary parts 3 and 4 at the top and bottom and movable members 5 and 6 similarly disposed at each side. In the form shown, the stationary members have parts projecting inwardly beyond the inner edge of the spacing member 2 so as to serve as top 55 and bottom retaining members for an insert

placed in the opening of the member 2. When the device is used with photographs or other matter in which it is desirable to keep the insert as flat as possible, the additional restraint afforded by these projections is desirable. However, in the event that this restraint is not required, the projecting parts may be omitted and the insert held entirely by the movable members 5 and 6.

10 The movable members 5 and 6 in this instance comprise T shaped tongues which are adapted to move laterally into and out of insert retaining position, sliding freely over the surface of the spacing member 2, and guided in their movements by extended portions 7 of the stationary parts 3 and 4, lying adjacent the stem portion of the T. Obviously any other suitable guide means for the movable members may be provided.

15 In order to limit the extent of lateral movement inwardly of the movable members, angular faces are provided at the ends of the elongated insert retaining parts as at 8 and 9. These faces are adapted to contact similar faces 10 and 11 carried by the stationary members 3 and 4, 25 so that when the parts are in insert holding position, as shown in Fig. 1, no space is noticeable between the parts. The outward movement of the movable members is, of course, limited by the extended parts 7 of the stationary members, 30 but may obviously be limited in any other suitable manner.

20 To finish the assembly and to restrict the movable members to a lateral sliding movement so that they cannot fall out of position, a suitable 35 finishing mat or overlay 13 is fixed to the stationary members 3 and 4. This part comprises a rectangular sheet having a central cut out approximately the size of the insert, and usually of an ornate configuration.

40 When it is desired to position an insert in the device, the movable tongues 5 and 6 are moved to their outer position, shown in Fig. 2, leaving the space defined by the stationary parts and the mat unobstructed. The insert is then slipped 45 under the stationary parts 3 and 4 of the underlay to rest against the mount 1 in the area defined by the spacing member 2 as shown in Fig. 4, the insert being designated by 14. It will be seen that the insert is held at its top and bottom by 50 the parts 3 and 4 when they are in this position. The movable members are next returned to the position shown in Fig. 1 so that the inner edges overlie the sides of the insert, thus completing a 55 frame entirely around it. Obviously in some in-

- stances the movable members alone will be sufficient to retain the insert in place, so that the inwardly projecting portions of the stationary parts 3 and 4 may be omitted.
5. In the event that it is desired to remove the insert, the movable tongues 5 and 6 are moved outwardly, exposing the sides of the insert, which may then be bowed to cause the insert ends to slip from under the members 3 and 4.
10. Obviously numerous changes may be made in the form and disposition of the parts, and I wish it expressly understood the invention is not limited to the specific embodiment shown, but includes all forms coming within the scope of the appended claims.
15. What is claimed is:
1. In a device of the class described, a mount, an insert receiving and holding means carried by the mount and including an underlay, an overlay, and means disposed between said underlay and overlay, said means having slidable parts for releasably engaging an insert.
  2. In a device of the class described, a mount, spacing means, stationary insert retaining means fixed to said spacing means, and movable retaining means cooperating with said stationary means to engage the insert when in one position and movable from engagement therewith when in another position.
  3. In a device of the class described, a mount, spacing means fixed to said mount, stationary insert retaining means fixed to said spacing means and having parts projecting inwardly beyond said spacing means, and movable insert retaining means having parts projecting beyond said spacing means to cooperate with said stationary means to hold the insert when in one position and movable outwardly beyond the edge of said spacing means to release the insert when in another position.
  4. In a device of the class described, a mount,

spacing means fixed to said mount, stationary insert retaining means fixed to said spacing means and having parts projecting inwardly beyond said spacing means, movable insert retaining means having parts adapted to cooperate with said stationary means to hold the insert, said means being movable outwardly to release the insert, and means carried by said stationary means to limit the extent of outward movement of said movable means.

5. In a device of the class described, a mount, stationary insert retaining means, means to space said stationary insert retaining means from said mount, and movable insert retaining means adapted to cooperate with said stationary means to hold the insert, said means being movable outwardly to release the insert.

6. In a device of the class described, a mount, stationary insert retaining means, means to space said stationary insert retaining means from said mount, movable insert retaining means adapted to cooperate with said stationary means to hold the insert, and means carried by said stationary means to guide and limit the movements of said movable means.

7. In a device of the class described, a mount, spacing means fixed to said mount, stationary insert retaining means fixed to said spacing means and having parts projecting inwardly beyond said spacing means, movable insert retaining means having parts adapted to cooperate with said stationary means to hold the insert, means carried by said stationary means to limit the extent of inward movement of said movable means, similar extending portions carried by said stationary means and fixed to said spacing means to limit the extent of outward movement of said movable means, and a mat fixed to said stationary means to limit said movable means to lateral sliding movements.
